GASOLINE PUMP

George B. Kamp, Springfield, Pa., assignor to Bowser,
Inc., Fort Wayne, Ind., a corporation of Indiana

Filed Aug. 31, 1961, Ser. No. 66,564

Term of patent 14 years

(Cl. D52—2)

FIG. 1

FIG. 2

FIG. 3

FIGURE 1 is a front perspective view of a gasoline pump showing my new design. The opposite side is substantially plain and the rear of the gasoline pump is substantially of the same appearance as the front shown.

FIGURE 2 is a front view of the gasoline pump shown in FIG. 1.

FIGURE 3 is a side elevational view of the gasoline pump shown in FIG. 1.

The panel bordering the top of the computer indicator face as seen in FIGS. 1 and 2 of the drawings is a plain opaque glass panel having spaced horizontal lines imprinted thereon and overlayed by a transparent glass panel.

I claim:

The ornamental design for a gasoline pump, as shown and described.
